P. H. GENTZEL.
AIR COMPRESSOR CONTROL.
APPLICATION FILED DEC. 6, 1919.

1,410,911.

Patented Mar. 28, 1922.

UNITED STATES PATENT OFFICE.

PERRY H. GENTZEL, OF NEWTON, MASSACHUSETTS.

AIR-COMPRESSOR CONTROL.

1,410,911.

Specification of Letters Patent. Patented Mar. 28, 1922.

Application filed December 6, 1919. Serial No. 342,942.

To all whom it may concern:

Be it known that I, PERRY H. GENTZEL, a citizen of the United States, residing at Newton, in the county of Middlesex, and State of Massachusetts, have invented certain new and useful Improvements in Air-Compressor Controls, of which the following is a specification.

My said invention consists in certain improvements in means for the relief of pressure in the compressed air tank, such as forms a part of a steam operated motor car, when said pressure has reached a predetermined point, whereby constant pressure of the degree desired may be maintained in said compressed air tank, all as will be hereinafter more fully described and claimed.

Referring to the accompanying drawings, which are made a part hereof, and on which similar reference characters indicate similar parts,

Figure 1 is a view partly in elevation and partly in section of one end of a compressor pump such as employed in the character of plant above referred to, and

Figure 2 top of plan view thereof.

In said drawings, the portions marked A represent the piston rod, B the pump cylinder, and C a relief valve casing.

The piston rod A is a continuation of the piston rod of the engine, and has a piston 10 thereon which operates in pump cylinder B continuously while the engine is in operation. At each end of said cylinder B on one side are mounted air intake valves 11 and 12 respectively, and on the other side are mounted discharge valves 13 and 14 respectively, which are connected with a pipe 15 leading to the compressed air cylinder or tank (not shown).

At each stroke of the piston 10 in one direction, the air will be sucked in through valve 11 and the air on the other side of the piston forced out through valve 14 into pipe 15 and into the compressed air cylinder. On the return stroke the air will be sucked in through the pipe 12 while the air sucked in during the previous stroke through valve 11 will be forced out through valve 13 into pipe 15 and to the compressed air cylinder.

Mounted on the top of cylinder B is a frame 16 supporting the relief valve casing or cylinder C. In said frame is mounted a reciprocating head 17, carrying transversely

extending arms 18 which are adapted to contact upon occasion with the upper ends of the valve stems 19 and 20 of the valves 11 and 12. Slides 30 connected with the reciprocating structure and mounted by slots therein on pins 31 on frame 16 serve to steady and guide the same. The head 17 is also connected by a ring or bearing sleeve 32 with a cam 33 on a shaft 34 provided with an operating arm 35 by which said head with arms 18 may be normally raised and lowered when desired, as will be presently described. Said sleeve 32 has a screw-threaded shank which extends through a perforation 60 in yoke 17 and has a nut 37 on its upper end for adjustment, as will be readily understood. A pipe 21 leads from the upper end of casing C to the compressed air cylinder. A sleeve 22 is mounted to reciprocate in said 65 casing C and is formed with a closed upper end against which the upper end of a rod 23 rests, said rod 23 being connected with the head 17 carrying the cross arms 18. Said rod 23 is normally held upward by means of 70 a spring 24 interposed between a flange on its upper end and a screw plug seated in the lower end of said casing. Said plug is mounted in said casing by screw threaded connections, and its adjustment thereby 75 serves to adjust the tension of said spring.

In operation, when it is desired to start the engine arm 35 is operated to open valves 11 and 12 and relieve the suction. After the engine is in operation the arms 18 are 80 raised to permit said valves to close and the operation of pumping air to the compressed air cylinder proceeds. When the air in the compressed air cylinder reaches a pre-determined pressure which pressure is determined 85 by the tension of said spring 24, then the pressure above the upper end of the piston 22 will overcome the pressure of said spring and force the head 17 carrying the arms 18 downwardly so that said arms will contact 90 with the upper ends of valve stems 19 and 20 and open valves 11 and 12, thus permitting the air to exhaust and the pump to run without suction and without forcing any more air into the compressed air cylinder until the 95 pressure therein has fallen to a point where the tension of spring 24 will overbalance said pressure and raise said arms 18 and close valves 11 and 12, or bring them to normal active position.

By this means the pump is allowed to run 100 constantly and the pressure is controlled au-

tomatically and maintained at the pressure desired, and the air circulation operates to keep the cylinder cool.

Having thus fully described my said invention, what I claim as new and desire to secure by Letters Patent is:

1. In an air-compressing mechanism, an air pump adapted to operate on both strokes of its piston to pump air into the compressed air cylinder, a casing mounted upon the pump adapted to house a reciprocating piston, a pipe leading from the air-cylinder and in operable communication with the piston, a spring for maintaining the piston in normal position, a piston rod operable with the piston provided with arms extending outwardly from both sides of the piston rod, spring-seated valves at both extremities of the pump for admitting air thereto, said valves being separable from but contacting with the extending arms and adapted to be held in unseated position by the arms when forced downward by the piston, a ring bearing adjustably secured to the piston rod, and a cam within the ring bearing adapted to be rotated by a hand lever for raising and lowering the piston rod and said extending arms.

2. In an air compressing mechanism, an air pump comprising a piston adapted to operate on both strokes of said piston rod to pump air into the compressed air cylinder, spring seated valves positioned at both ends of the pump, a casing mounted upon the pump, a reciprocating piston within the casing, a piston rod operable with the piston having outwardly extending arms adapted to contact and depress the said valves, a spring for normally holding said arms out of contact with said valves, and means for manually raising or lowering the reciprocating parts to simultaneously throw the arms out of engagement with the valves or depress them.

In witness whereof, I have hereunto set my hand and seal at Boston, Massachusetts this twenty-first day of November, A. D. nineteen hundred and nineteen.
